GUMMED PAPER MEASURING, TEARING AND MOISTENING TOOL

Lois D. Elkins, 1603 Caroline St., Fredericksburg, Va.

Filed Sept. 4, 1963, Ser. No. 76,474

Term of patent 14 years

(Cl. D52—1)

FIGURE 1 is a top plan view of the gummed paper measuring, tearing and moistening tool, showing my new design;

FIGURE 2 is a bottom plan view thereof;

FIGURE 3 is an end elevational view thereof; and

FIGURE 4 is a side elevational view thereof.

I claim:

The ornamental design for a gummed paper measuring, tearing and moistening tool, as shown.
